COUPLING MEANS FOR USE WITH CALCULATING, BOOKKEEPING, OR LIKE MACHINES

Rolf Hofgaard, Nordstrandshogda, near Oslo,
NorwayApplication December 5, 1946, Serial No. 714,295
In Norway May 1, 1946

3 Claims. (Cl. 235—61)

1

The present invention relates to a coupling arrangement adapted to be used in electrical calculating machines, bookkeeping machines, coding and decoding machines, statistic machines, etc., and the object of the invention is to provide a coupling arrangement for machines of this type in which numbers or letters are indicated by code signs, the individual elements of which may be combined to indicate a predetermined number or other value.

One object of the invention is to provide a coupling arrangement of this type which is adapted to carry out the necessary operations solely by means of switches or contacts connected in the different circuits of the coupling arrangement.

A further object of the invention is to provide a coupling arrangement of the kind specified which is adapted to operate with a minimum number of relays and contacts and which is therefore simple and reliable.

The coupling arrangement in accordance with the present invention principally has for its object to connect one or more of a number of electrical circuits (output circuits) with a source of current in such a manner that the circuits are selected on one hand in accordance with electrical impulses supplied in accordance with a predetermined code and on the other hand in accordance with the circuit or circuits which have been connected to the source of current during a previous operation.

In accordance with the invention the coupling arrangement comprises two sets of electro-magnetically controlled switch relays interconnected in series, one set being adapted to receive impulses from an exterior source and the other set being adapted to transmit the impulses which have passed the first set of relays.

The number of relays in the first set corresponds to the number of units in the code utilised for introducing impulses, whereas the number of relays in the second set corresponds to the number of output circuits which may be equal to or different from the number of units in the code system used for introduction of impulses.

The relays in the second set of relays are so connected with the output circuits that they are actuated by electrical impulses from those output circuits which are connected with the source of current.

The relays used in connection with the present coupling arrangement may be of any convenient type of electro-magnetically controlled multiple contact relays, i. e., contact relays which simultaneously interrupt or close a number of contacts when actuated by an electrical impulse.

It is preferred to use a relay of the type which is described in applicant's co-pending application

2

Serial No. 714,070, filed December 4, 1946, and provided with a mechanically operated driving member and an electro-magnetic control mechanism which co-operates in such a manner that contacts of certain switches are moved from normal position to working position against spring action by means of the mechanical driving member and remain locked in working position when the electro-magnet is energized and are released from their working position so as to be moved back to normal position by spring action when the electro-magnet is de-energized.

This type of relay has the advantage amongst others that it will operate effectively by means of relatively weak electro-magnetic impulses.

In the accompanying drawing is diagrammatically illustrated how the present coupling arrangement may be used in connection with an electrical calculating machine for addition and subtraction using a decadic system of numbers and a code comprising the digits 1—2—2—4, by means of which all digits in the decadic system of numbers may be indicated.

Referring to the accompanying drawing
25 Figure 1 is a coupling diagram,

Figures 2 and 3 illustrate a practical embodiment of the multiple contact relays used in normal position and working position respectively, and

Figure 4 illustrates on a smaller scale a set of
30 such multiple contact relays corresponding to that illustrated in the coupling diagram.

In the coupling diagram the digits in parenthesis are the digits of the code system used, whereas the other numerals relate to the different
35 parts of the arrangement.

The coupling arrangement comprises two sets of multiple contact relays 11, 12, 13, 14 and 15, 16, 17, 18, the first of which are controlled by intake circuits and correspond to the digits 4, 2, 40 2 and 1 in the code system, whereas the second set controls the output circuits and corresponds to the digits 1, 2, 2, 4 in the same code system.

Further, the coupling arrangement comprises an auxiliary relay 19, the object of which is to 45 perform the couplings necessary for a carry transfer operation.

The intake circuits are indicated at 20, 21, 22, 23 and may be supplied with electrical impulses from a suitable coupling box 24 which is connected by 50 means of a line 25 to the plus terminal of a battery 26.

Each of the intake lines 20—23 are connected with electro-magnetic switches 27—28, 29—30, 31—32, 33—34 and corresponding electro-magnetic switches 35—36, 37—38, 39—40, 41—42 and 43—44 are arranged in connection with multiple contact relays 15, 16, 17, 18 and 19.

The output lines from the coupling are indicated with 45, 46, 47 and 48 and represent the

digits 1, 2, 2 and 4 in the code system used for the intake lines.

Each multiple contact relay comprises a number of contact arms which, when the relay receives an impulse, are moved from a resting contact to a working contact. In connection with multiple contact relay 11 a number of such contacts are illustrated such as for instance resting contact 49, working contact 50 and the movable contact arm 51. When a current passes through line 20, the relay 11 is cut in by means of electro-magnetic switch 27, 28 and the contact arms in this relay then move from resting position to working position, for instance by movement of contact arm 51 to working contact 50. As it appears from the coupling diagram, the electro-magnetic switch 27, 28 is self-closing so that after having received an impulse it maintains the corresponding relay in working position until the contact is interrupted by mechanical means as will be described in connection with Figures 2-4.

A line 52 by means of a switch 53 may be connected to the plus line 25 of the battery, whereby a contact device 54, 55, 56 is connected in the circuit instead of the contact device 49, 50, 51. This coupling takes place when the coupling arrangement is to be used for subtraction instead of addition.

Further, the multiple contact relay 11 comprises two contact systems 57, 58 and 59, 60, the function of which is connected with a carry transfer operation.

Each of the multiple contact relays 11-19 may suitably be carried out as illustrated in Figures 2 and 3, and the relays may be placed with relation to each other as diagrammatically illustrated in Figure 4.

The multiple contact relay comprises a number of contact arms 200 which in the normal position, as illustrated in Figure 2, engage contact springs 201. This is the position of the relay contacts illustrated in Figure 1.

On the opposite side of each contact arm 200 are located contact springs 202 and these as well as contact springs 201 are connected at their top ends with an illustrated block 203.

The block 203 carries a pivoted arm 204 which when it is turned from the position illustrated in Figure 2 to the one illustrated in Figure 3 is brought into the path of a reciprocating mechanically driven actuating member 205.

The movement of the arm 204 is controlled by an electro-magnet 206 corresponding to electro-magnets 27-29 . . . 41-42 in Figure 1, the armature of said electro-magnet being adapted when attracted to swing the arms 204 into the position illustrated in Figure 3.

Member 205 will then press the arm 204 and the block 203 towards the left so that contact is made with the contact springs 202 as illustrated in Figure 3.

In this position a hook 207 grips in behind a nose 208 on the arm 204 and thereby locks the parts 203, 207 in the position illustrated in Figure 3 irrespective of whether the electro-magnet 206 is energized or not.

Upon its next stroke the mechanical actuating member 205 will press the hook 204 slightly towards the left, and if the electro-magnet is then not energized, the armature 207 and the whole contact set will move back into the position illustrated in Figure 2.

In case the electro-magnet is energized, the different parts of the relay will, however, remain in

the position illustrated in Figure 3 (the working position).

On the armature 207 is mounted an arm 209 which engages with its lower end a contact spring 210. When the armature 207 is attracted, the arm 209 presses contact spring 210 against another contact spring 211 and thereby establishes a self-closing circuit for the electro-magnet as indicated in Figure 1, for instance at electro-magnet 27 and armature 28.

In connection with the coupling illustrated in Figure 1, the relay operates in such a manner that an electrical impulse for instance in one of lines 20-23 energizes the electro-magnet so that the relay contacts are carried from normal to working position. The movement of the mechanical actuating member is synchronized in such a manner with the impulses supplied that it performs one full reciprocating stroke for each impulse, and 20 the relays, the electro-magnets of which are energized, will then either be moved into or maintained in working position, whereas the other relays are either moved to or caused to remain in normal position.

25 The self-closing contacts 210, 211 may be connected in series with the contacts 200, 201 so that the self-closing circuit is broken when the relay contacts are in working position.

All relays 11-19 as indicated in Figure 4 are 30 mounted closely adjacent and in line with each other and the actuating members 205 are formed by the hooks 214 or the like mounted on a common reciprocating bar 212 deriving its movement from an eccentric 213.

35 In the following it will be indicated by an example how a simple calculating operation may be carried out by means of the coupling arrangement above described.

It is to be presumed that the following calculating operation is to be carried out:

$$8-2+7=13$$

First the digit 8 is introduced, this digit being composed by the code elements 4, 2, 2 and 45 accordingly relays 11, 12, 13 are moved from normal to working position by means of impulses through lines 20-21-22.

The following circuits are then closed: Plus terminal of the battery, lines 25-61-62-63-64-

50 65-66-67-68-46, through 68 and 70 to the electro-magnet switch 37-38, whereby relay 16 is connected in working position. Current also passes through line 65 over 71-72 to 47 and from there through 73 to electro-magnet switch 39-40,

55 whereby relay 17 is connected in working position. Further from 65 over 74-75-76 to 48 and from there over 77 to electro-magnet switch 41-42, whereby relay 18 is energized in working position.

60 The introduction of digit 8 by means of impulses on intake lines 20-21-22 accordingly have connected the corresponding output lines 46-47-48 with the plus terminal of the battery and at the same time brought moving relays 16-17 and 18 representing the code digits 2, 2 and 4 into working position.

65 As the next operation to be carried out is the subtraction of 2, line 25 is connected by means of switch 53 with line 52, whereby those contacts in all relays are cut in which serve to carry out subtraction in accordance with the well known principle of adding the complementary value of the subtraction.

The output lines from the last intake relay accordingly for subtraction are directly connected

with output lines corresponding to the complementary values in the addition circuits.

By connecting line 52 in accordance with the subtraction system to be used and which does not form a part of the present invention, current is supplied to output lines 47-48, whereas output line 46 is cut out, current being instead supplied to output line 45 and at the same time relay 19 (the carrier relay) is moved into working position.

Instead of output lines 46, 47, 48 corresponding to the digit 8 first introduced there is accordingly now current on output lines 45, 47, 48 corresponding to digit 7+ carrier digit 1.

This particular method of coupling has certain practical advantages which need not be discussed as it is possible in connection with the coupling arrangement in accordance with the invention to use even other methods of subtraction which are known from other automatic addition and subtraction systems.

The digit 2 is now introduced by means of an impulse through line 22, whereby relay 13 is energized and the following current circuits are closed: 25-52-78-79-80-43+44. When electro-magnet 43 receives current, relay 19 remains in working position.

Further, there is closed a circuit 25-52-78-81-82-100 to 45 and through 85 to electro-magnet 35, whereby relay 15 is connected in working position. There is also closed a circuit 25-52-86-87-88-103-89-65-74-93 to 48 and from there over 71 to electro-magnet 41 so that relay 18 still is cut into working position. Further, there passes current over 88-94-104-105-97-110 to 97.

The current impulse hereby supplied to carry line 97 passes to the next set of relays which is in all essentials identical with the set of relays illustrated in Figure 1. The effect of the first carry impulse to the next set of relays is to move this set into zero position as in accordance with the method of subtraction referred to above it is automatically put in the position corresponding to 9 by moving switch 53 into subtraction position. The next set of relays which, as it will be understood, corresponds to a higher unit (tenths) is accordingly now in position for taking up the next carry impulse.

As the next operation is to be carried out as an addition, switch 53 is again brought into the position illustrated on the drawing and digit 7 is introduced by current impulses on lines 20-21-23 representing the code digits 4-2 and 1. Of the remaining relays 15-18 and 19 remain in working position since the previous operation.

The following current circuits are now closed: 101-102-89-65-66-67-68-46 and further 102-103-94-104-105-97.

The result of the operations heretofore discussed consequently will be that the output lines 45-46 representing code 1+2=3 are under current whereas at the same time the carry impulse through line 97 to the next set of relays has put the output line 45 of that set of relays under current.

The number 13 is accordingly now introduced into the two first sets of relays of the system.

The calculating example given above has only the object of understanding how the coupling arrangement in accordance with the present invention may be utilized in connection with addition and subtraction.

For those skilled in the art it will be easily understood that the various calculating opera-

tions may be carried out by utilizing the principle forming the basis for the coupling arrangement of the present invention.

It will also be understood that in connection with the coupling diagram which has herein been illustrated as an example, it will be necessary in some of the connection lines to use one-way valves (such as selenium rectifiers or the like) in order to prevent undesired transmission of current impulses through the lines connected to the first relay in the second set of contact relays.

The use of one-way valves in one or more of the transmission lines is here not necessary for the general function of the system, and they may for instance be obviated by using the same number of current intakes and contact groups in the first set of relays as in the second.

I claim:

1. A coupling arrangement for electrical computing apparatus comprising a set of electromagnetically controlled input relays, the number of input relays being equal to the number of units in a code system, means for selectively energizing said relays in accordance with numeral values to be entered in the apparatus, sets of contacts controlled by the respective input relays, the sets of contacts of the last input relay including contacts significant respectively of each code value, a source of current, connections between said sets of contacts to connect said current source to those contacts of the last relay corresponding to code values of the energized input relays, a plurality of output electrical circuits, a set of electromagnetically controlled storing relays equal in number to the plurality of electrical output circuits, sets of contacts controlled by the respective storing relays, the first storing relay having contacts corresponding to and connected respectively to the contacts of the last input relay, and connections between the sets of contacts of the storing relays and to said output circuits to complete circuits from said current source to those output circuits corresponding to the numerical value represented by the selectively energized input relays, said last mentioned circuit connections also completing circuits to energize those of the storing relays corresponding to the accumulated numerical value entered at said input relays.

2. A coupling arrangement as recited in claim 1, wherein each of said electromagnetically controlled relays includes a solenoid and an armature movable thereby into operative position on energization of the solenoid, said sets of contacts include switch blades movable between front and back contacts, and mechanical reciprocating means cooperating with relay armatures in operative positions to shift the switch blades of the sets of contacts of energized relays into engagement with their front contacts.

3. A coupling arrangement as recited in claim 1, wherein the number of electrical output circuits is equal to the number of input relays.
